DESIGN FOR A FAN CASING

Henry Thomas and Charles F. Lockwood, Buffalo,
N. Y.

Application February 7, 1938, Serial No. 74,923

Term of patent 14 years

To all whom it may concern:

Be it known that we, Henry Thomas and Charles F. Lockwood, both citizens of the United States, and both residing at Buffalo, in the county of Erie and State of New York, have invented a new, original, and ornamental Design for a Fan Casing, of which the following is a specification, reference being had to the accompanying drawing forming part thereof.

In said drawing:

Fig. 1 is a side elevation of the fan casing embodying our design.

Figs. 2 and 3 are front and rear end elevations, respectively, of the same.

Fig. 4 is a perspective view thereof.

We claim:

The ornamental design for a fan casing as shown.

HENRY THOMAS.
CHARLES F. LOCKWOOD.
